M. E. LOHR.

HOISTING APPARATUS,

APPLICATION FILED NOV. 6, 1920.

1,394,915.

Patented Oct. 25, 1921.

Inventor

Michael Earl Lohr:

By Geo. E. Thackray,
Attorney

UNITED STATES PATENT OFFICE.

MICHAEL EARL LOHR, OF WESTMONT BOROUGH, PENNSYLVANIA.

HOISTING APPARATUS.

1,394,915.

Specification of Letters Patent.

Patented Oct. 25, 1921.

Application filed November 6, 1920. Serial No. 422,131.

To all whom it may concern:

Be it known that I, MICHAEL EARL LOHR, a citizen of the United States, residing in the borough of Westmont, in the county of Cambria and State of Pennsylvania, (whose post-office address is Johnstown, Pennsylvania,) have invented certain new and useful Improvements in Hoisting Apparatus; and I do hereby declare the following to be a full, clear, and exact description, such as will enable others skilled in the art to which it appertains to make and use the same.

My invention relates to hoisting apparatus with particular reference to that class of the same which uses a car or bucket which is hoisted and lowered by a cable, chain or other flexible member attached thereto, and which bucket is arranged to dump its contents at a predetermined height into a bin, hopper or otherwise for further use or disposal of its contents.

My bucket or container may either travel vertically or at an inclination as desired, as will be readily understood, but for the purpose of simplicity of the drawings and description I will confine the same to travel which is substantially vertical.

My bucket is preferably provided with a lower wheel or pair of wheels adapted to roll in or be guided by an upright guide or a set of upright guides, and an upper wheel or pair of wheels which are arranged to be guided by another upright guide or another set of upright guides, and when the bucket reaches the ordinary upper limit of its travel the upper wheels are deflected from their prior position by annular or curved guides in such a way as to overturn the bucket to discharge its load, and upon lowering the bucket the wheels return into the upright guides and the bucket assumes its upright and lower position to receive a further load.

The cable which hoists and lowers my bucket may be operated by any suitable winding apparatus (not shown) and may be provided with an automatic or manually controlled stop as desired to stop the travel of the bucket when desired. The winding apparatus may have a limit switch for the upward movement of the bucket and for the lower position of the bucket, or the upper, lower or either switch may be secured to the

hoisting frame and adapted to be operated by the bucket or projections on the bucket itself, but this forms no part of my invention and it is not necessary to illustrate the same.

However, I have discovered that with such an apparatus the travel of the bucket of a hoist whether automatically or manually stopped cannot always be exactly controlled, and particularly when the load in the bucket is lighter than usual there will be a tendency to a considerable over-travel at the upper point, which by reason of the prior constructions will wreck the apparatus or the guides of same, the bucket or portions thereof, or break or strain the cable or the hoisting drum and its attachments.

In order to obviate this difficulty I provide special forms of dumping guides which coöperate with the wheels of the bucket and also provide an excess height of the other guides so that any reasonable over-travel of the bucket may be allowed, which will obviate the difficulties above mentioned. I also provide one or more contact fingers which may be of curved or other form secured to the bucket, which coöperate with a roller or stop secured to the frame near the dumping guides so that even should the bucket have an over-travel the guide wheels of same will remain in their proper and respective guides both during the upward over-travel and the downward return, thereby absolutely insuring the easy movement of the bucket in its over-travel and its smooth return without shock to its lowering position.

Having thus given a general description of my invention I will now, in order to make the same more clear, refer to the annexed sheet of drawings which forms part of this specification and in which like characters refer to like parts.

Figure 1 is a rear elevation of a portion of a hoisting frame with my improved apparatus attached thereto, illustrating the application of my invention; Fig. 2 is a side elevation of the same portion of the hoisting apparatus shown in Fig. 1; Fig. 3 is a side elevation on a larger scale of one of the dumping guides and the adjoining

parts of the hoisting frame; Fig. 4 is a detail view on a larger scale of the stop shaft; and Fig. 5 is an enlarged detail sectional elevation of one of the rear wheels of the bucket and the bracket bearing therefor, also showing one of the channel guideways and the position of the wheel therein.

Referring now to the characters of reference on the drawings, 1 represents the frame 10 of the hoist in general, 2 are the hoist beams mounted and secured on the top of the frame as illustrated, 3 are journal bearings mounted on the hoist beams, 4 is the shaft which is journaled in the bearings 3 and 15 which carries the hoisting sheave 5 thereon. 6 is the upper brace of the hoist frame, 7 is the cable secured at one end to the hoist bucket, while the other end of same passes around the winding drum of a hoisting engine which may be driven in any manner desired and which may be provided with automatic controls for stopping the bucket in its upper or lower positions, or may be manually controlled as aforesaid. 8 is the 20 bucket which ordinarily is known as a skip bucket, 9 is the upper portion of the bail of said bucket, 10 is the pivotal connection whereby the cable is attached to the upper portion of the bail of the bucket, 11 are the 25 upper guide wheels mounted on the bucket, 12 are the lower guide wheels also mounted on the bucket and 13 are the axles for the wheels 11 and 12. Each of the wheels is provided with a recess 14 in the outer portion 30 thereof in order to provide space for the retaining nut 19 which is secured on the end of the shaft or axle 18. 15 are the side portions of the bucket bail, the lower portions of which are each provided with an 35 eye-end and each is further provided with a roller bearing 16 whereby they are mounted on the lower axles 13. 17 are bearing plates secured to the sides of the bucket and in which are mounted the axles 13 which 40 are secured therein by means of the pins 18. 45 20 are channel guideways for the lower wheels of the bucket, which guideways are illustrated as upright and substantially straight, 21 are the channel guideways for 50 the upper bucket wheels, the lower portions of which are also upright and substantially straight, but these connect with the curvilinear guideways 27 and also have upwardly extending straight portions 22. 23 is an intermediate brace and support shown as of channel form adapted to hold the parts of 55 my construction together, while 24 are large gusset plates secured to the framework and to the curved guides 27 to hold said guides 60 in position, and the outer ends of the curved guides are 26. Secured to the gusset plates 65 are the angle pieces 28 and 29 on the inner and outer faces thereof, and secured to and mounted upon the angles 28 are the 65 bearings for the stop shaft 30, which is pro-

vided with rollers 32 mounted on said shaft, which rollers are further provided with collars 33 on each side thereof.

Secured to the bucket are the contact fingers or cams 34 which are adapted to co-operate with the rollers 32 and maintain the wheels of the bucket in their proper guides for smooth and effective operation as previously described. The upper portions of the guideways 20, and 22 may be of any 75 length desired to provide over-travel to any degree.

Having thus given a description of my apparatus, I will now explain its operation:—The bucket being in its partly lowered position, as illustrated in Figs. 1 and 2, is hoisted with a full or partial load into the dumping position as shown by dotted lines in Figs. 2 and 3, whereupon the lower wheels 12 of the bucket travel upwardly 85 within the channel guides 20, while the upper wheels 11 are guided into the curved guides 27 and outwardly toward the outer portions 26 thereof, causing the bucket to be dumped to discharge its load. At the same time the curved contact fingers 34 90 contact with the rollers 32 and assist in maintaining the bucket and its wheels in the position illustrated in dotted lines in Figs. 2 and 3. In case the bucket should over-travel, due to over-winding, the lower wheels 12 will move upwardly to any necessary extent within the upper portion of the channel guides 20 while the upper wheels 11 will travel upwardly in the upper portions 27 of the curved guideways and this action is insured by the engagement of the contact fingers 34 with the surfaces of the rollers 32, thus insuring the travel of the upper wheels 11 within the upper portion 100 of the curved guideways 27, and if the travel is continued these upper wheels will also move upwardly to a further extent within the upper portions 22 of the guideways. 105 When the bucket is being lowered the operation is reversed, and the action of the contact fingers 34 against the guide rollers or roller stops 32 also insures the maintenance of the wheels 11 within the lower portions of the curved guideways 27, thence into the upright portions 21. By means of this apparatus all the difficulties connected with the over-travel of the bucket are obviated.

Although I have shown and described my invention in considerable detail, I do not 120 wish to be limited to the exact and specific details thereof, as shown and described, but may use such modifications in, substitutions for, or equivalents thereof, as are embraced within the scope of my invention, or as 125 pointed out in the claims.

Having thus described my invention, what I claim and desire to secure by Letters Patent is:—

1. A hoisting apparatus comprising a 130

dumping bucket provided with upper and lower guide wheels rotatably secured thereto, upright guideways coöperating with the lower guide wheels and extending above the

- 5 upper limit of travel of said bucket, guideways coöperating with the upper guide wheels and provided with curved portions adapted to over-turn said bucket, the lower curved portions of the last mentioned guideways being connected with upwardly extending curved portions which merge into a further upright extension of same, a guide roller mounted on the frame-work, and a contact finger secured to the bucket and
- 10 adapted to coöperate with said guide roller, whereby the guide wheels of the bucket are constrained to move within their respective guides.

2. A dumping bucket provided with upper and lower guide wheels secured thereto, guideways coöperating with said wheels and extending beyond the ordinary travel of said bucket, curvilinear guideways adapted to guide the upper guide wheels to dump said bucket, a stop mounted on the hoist frame, and a contact finger on said bucket adapted to engage said stop; whereby the guide wheels are retained within their respective guideways during the dumping, 30 over-travel and return of the bucket.

3. A hoisting apparatus comprising a dumping bucket provided with upper and lower guide wheels rotatably mounted thereon, guideways adapted to guide said wheels and extending beyond the ordinary travel of said bucket, the guideways for the upper wheels being each provided with a curvilinear portion adapted to dump said bucket, a roller stop mounted on the hoist frame, a contact finger secured to said bucket and adapted to engage said roller

stop whereby the guide wheels are retained within their guideways during the dumping, over-travel and return of the bucket.

4. A hoisting apparatus comprising a hoist frame and dumping bucket with hoisting and lowering mechanism therefor, said bucket being provided with a pair of upper and a pair of lower guide wheels rotatably mounted thereon, guideways adapted to 50 coöperate with said guide wheels and extending beyond the ordinary travel of said bucket, the guideways for the upper guide wheels being provided with curvilinear portions, adapted to dump said bucket, 55 roller stops mounted on the hoist frame, and curvilinear contact fingers secured on said bucket adapted to engage said stops; whereby the guide wheels are retained within their guideways during the dumping, 60 over-travel and return of the bucket.

5. A hoisting apparatus comprising a hoist frame provided with guideways extending beyond the ordinary limit of travel of the hoist bucket, a hoist bucket provided 65 with upper and lower guide wheels rotatably mounted thereon and adapted to travel in and be guided by the guideways aforesaid, the guideways for the upper wheels being provided with curvilinear portions 70 arranged to dump the bucket at a predetermined location, a curvilinear contact finger mounted on the bucket, and a stop roller mounted on the hoist frame adapted to engage said contact finger; whereby the guide 75 wheels are maintained within their guideways during the dumping, over-travel and return of the bucket.

In witness whereof I hereunto affix my signature.

MICHAEL EARL LOHR.
